FIG. 5.

UNITED STATES PATENT OFFICE.

LYMAN R. ROBERTS, OF RUTHERFORD, NEW JERSEY, ASSIGNEE TO UNDERWOOD TYPEWRITER COMPANY, OF NEW YORK, N. Y., A CORPORATION OF DELAWARE.

TYPE-WRITING MACHINE.

1,110,825.

Specification of Letters Patent. Patented Sept. 15, 1914.

Application filed March 10, 1913. Serial No. 753,234.

To all whom it may concern:

Be it known that I, LYMAN R. ROBERTS, a citizen of the United States, residing in Rutherford, in the county of Bergen and State of New Jersey, have invented certain new and useful Improvements in Type-Writing Machines, of which the following is a specification.

My invention relates to power-operated means for actuating the type bars of a type-writing machine, and more particularly to pneumatically actuated mechanism for operating the type bars.

The invention provides a construction in which all of the type bars may be actuated by power supplied by a single bellows or pneumatic motor, which is adapted to intermittently operate the type bars through intermediate mechanism comprising selective devices, set by the operation of the key levers into position to be operated by the motor, and in turn actuate the type bars. The selective devices are automatically locked in set position and released by the operation of the motor, thereby insuring the operation of each selective device before it is returned to inoperative position.

In my co-pending application Serial No. 749,297, filed February 19, 1913, the type actions are electromagnetically operated. In the present application, a series of operating bars, one for each type key, are adapted to be selectively operated or set by the key levers into position to be actuated by a pneumatically operated rotary driver and thereby operate the type bars. The operating bars are vertically disposed and rest on the ends of the key levers. When a key lever is operated, it lifts its bar and releases a locking pawl from an actuating arm pivoted to the type bar, and also operates to open a valve controlling the pneumatic action, and thereby permits an air motor or bellows to be operated and rotate the driver to throw the lifted bar forward and actuate the type bar. A locking latch holds the key lever in operated position and the bar lifted until the pneumatic has operated the bar, which operation releases said latch and per-

mits the key lever and bar to be restored to initial position.

Other features and advantages will hereinafter appear.

In the accompanying drawings, Figure 1 is a perspective view illustrating the pneumatically operated power mechanism for actuating the type bars. Fig. 2 is a detail view of the pawl and ratchet mechanism. Fig. 3 is a sectional elevation view of the mechanism shown in Fig. 1 and the pneumatic mechanism, and also shows the relation of the type bars and keys to the actuating mechanism, the parts being in their normal positions of rest. Figs. 4, 5 and 6 are views similar to Fig. 3, but showing the parts in different positions assumed successively during the actuation of a type bar. Fig. 4 shows the position of the parts when a key lever has been depressed, but before the power device comes into operation. Fig. 5 shows the position of the parts when a type bar is in an intermediate position during its printing stroke. Fig. 6 shows the position of the parts at the instant the type bar has completed its printing stroke.

Finger keys 1 are provided at the forward ends of key levers 2 mounted on a pivot rod 3 which is normally held against a stop 4 by means of springs 5. The rear ends of the key levers extend into or through vertical slots 6 formed in a vertical plate or wall 7 which extends across the machine and is rigidly secured to or forms part of the framework of the machine.

Type bars 8 are fulcrumed on a pivot rod 9 and carry types 10 adapted to be brought into printing relation with a platen 11. Pivotally connected to each type bar, by means of a pin 12, is an actuating arm 13 also connected to the type bar through a returning spring 14. The wall 7 is provided with slots or kerfs 15 in which the rear ends of the arms 13 are guided. Guide pins or rods 16 and 17, located respectively below and above the arms 13, serve to guide the rear ends of said arms in a substantially horizontal direction. The relative arrangement, form and position of the type bars, arms 13

and associated parts may be the same as that shown in Fig. 7 of my co-pending application above referred to, No. 749,297.

Each type bar and its actuating arm 13 are locked in their normal position of rest by means of a locking pawl 18, pivoted at 19 in a slot 15, and held in locking position by gravity assisted by a spring 20. The pawl is formed with a nose 21 which seats in a corresponding notch in the free end of the arm 13.

Between each key lever and the corresponding arm 13 is a vertically disposed operating bar 22. These operating bars are formed with upper and lower openings 23 and 24 respectively, through which extend supporting and guiding rods 25 and 26 mounted in supports 27. These supports may be in the form of ribs formed on the plate 7, said ribs having slots in alignment with the slots 6 and 15. The openings 24 are in the form of vertical slots which permit a free vertical movement of the bars 22, and also permit the bars to be tilted forwardly about the rods 26 as a fulcrum. The openings 23 are of such size and shape as to permit a free vertical and tilting or transverse movement of the bars.

When a key 1 is depressed, it throws the corresponding bar 22 upward to the position shown in Fig. 4, and releases the locking pawl 18 so that the type bar is free to be actuated, the upper end of the bar 22 by such upward movement being positioned behind the arm 13 for actuating the latter and throwing the type bar upward to printing position when the bar 22 is thrown forward, as hereinafter set forth.

When a finger key is depressed, it is locked in such position by a lever or latch 28 pivoted on a universal rod 29, and formed with a shoulder 30 which is carried beneath the end of the key lever by a spring 31, whereby the bar 22 set by the key lever is held up until it is actuated by the rotary driver.

The type bars are operated by power supplied by pneumatic mechanism comprising a bellows 32 and valve mechanism controlling the supply and exhaust of air to and from the bellows. A pipe or passage 33 extends from the bellows to a valve chamber 34 in which is located a vertically movable valve 35. The valve 35 is normally seated by gravity and closes a valve port or opening 36, which forms a communication between the valve chamber 34 and an exhaust chamber separated by a diaphragm 38 into upper and lower compartments 37 and 39. An exhaust pipe 40 comprises branches 41 and 42 communicating with said upper and lower compartments 37 and 39 respectively. The exhaust pipe 40 leads to a vacuum pump or vacuum chamber, whereby the air is normally exhausted from the compartments 37

and 39. A pipe 42' leads from the compartment 39 to a valve 43, pivoted at 44 to a stationary support, and adapted to be lifted by a spring 45 into position to close the passage 42'.

The bellows 32 comprises a rigid back 46 and a front plate 47 pivotally connected thereto in the usual manner by collapsible sides 48.

When a key is depressed to set an operating bar 22, a lug 49 on the bar lifts a universal rod 50, which extends transversely over the lugs 49, and thereby swings a lever 51, connected to the rod 50, about its stationary pivot 52. A tail 53 of the valve 43, in the path of the lever 51 is struck by the lever and opens the valve 43. This admits atmospheric pressure through the pipe 42' into the compartment 39. The unbalanced pressure thus produced on the diaphragm 38 lifts the valve 35 to open the port 36, and also causes the upper end of said valve to close a port 54 opening from the valve chamber 34 to the outside air. The port 36, being opened, permits the air to be exhausted from the bellows through the passage 33, 34, 36, 37, 41 and 40. The passage 42 is sufficiently restricted to prevent the pressure in the compartment 39 being reduced enough during the operation of the bellows to allow the valve 35 to drop.

When the valve 43 has again been closed after the operation of the bellows, a partial vacuum is produced in compartment 39 reducing the pressure on the under side of the diaphragm 38, and permitting the valve 35 to move downward to its initial position; this movement being assisted by the atmospheric pressure at the upper side of the valve. The port 54 being thus opened and the port 36 closed, air will enter port 54 to again inflate the bellows. A pin-hole or bleed-hole 55 in the diaphragm 38 serves to quickly establish a balance of pressure on opposite sides of the diaphragm when the valve 43 is closed.

The bellows is connected through a link 56 to a lever 57 secured to a rock shaft 58 which may be journaled in the frame of the machine. A pawl 59 connected by a pivot 60 to the lever 57 is adapted to actuate a ratchet wheel 61 secured to an axle 62 of a rotary driver shown in the form of a reel. This reel comprises a series of horizontal rods 63 equally spaced and symmetrically arranged with respect to the axle 62. The ends of the rods 63, as shown in Fig. 1, are secured to a spider 64 to which is also secured the axle 62. At intermediate points the driver may be provided with one or more plates 65 to properly space and rigidly hold the rods 63 in position.

The ratchet wheel 61 is formed with ratchet teeth 66 corresponding in number and posi-

tion to the rods 63. The pawl 59 is yieldingly held in a position perpendicular to the lever 57 by means of a leaf spring 67 secured to the lever and bearing against the squared 5 end of the pawl. The ratchet wheel carries on its outer face a series of pins 68 in position to coöperate with a stop 69 secured to the lever 57.

When the lever 57 is operated, the pawl 10 59 rotates the wheel through an angle corresponding to the distance between the two adjacent rods 63, and the stop 69 is brought over a pin 68 to positively limit the movement of the driver, and thereby prevent 15 overthrow. The inward movement of the lever 57 is limited by an adjustable stop 70 consisting of a set screw in a stationary bracket 71, the latter being formed with a slot 72 in which the lever is guided. The 20 bracket 71 may also carry a back stop 73 of felt, rubber or other suitable cushioning and sound deadening material.

The operation may be reviewed as follows: When a key is depressed, the corresponding 25 operating bar 22 is set, that is, lifted from the Fig. 3 position to the Fig. 4 position, and locked by the latch 98. This movement of the bar 22 lifts the locking pawl 18 so that the corresponding type bar is free to be actuated. A shoulder or bearing surface 74 of the bar 22 is at the same time brought directly in front of a rod 63 of the driver. As the bar is lifted, it also operates the lever 30 51 to open the valve 43, and thereby effect the operation of the bellows as previously described; the bellows in turn operating the lever 57 and rotating the driver. This movement of the driver throws the upper end of the operating bar 12 forward, thereby moving 35 the actuating arm 18 forward and throwing the type bar up to the platen. As the operating bar moves forward, the rod 63 by which it is actuated is carried above the shoulder 74, and thus releases the bar for its 40 return movement. In Fig. 5 the parts are shown in the position assumed just before the bar is released, or in other words, near the completion of the positive stroke of the bar. After the operating bar is thus released, the type bar completes the printing 45 stroke by its momentum.

The movement of the operating bar, when actuated by the driver, is about the pivot 26 as a fulcrum, so that the lower end is moved 50 rearwardly and releases the latch 28, thereby permitting the bar to drop and the key lever to be restored. As the bar drops, a spring 75 returns the lever 51 and permits the valve 43 to close. The bellows is then inflated as above described, and the lever 57 returned by means of a spring 76, which may also aid in moving the bellows to initial 55 position. A spring-pressed arm 77, positioned to engage between two adjacent rods

68 of the driver, serves to accurately adjust 60 the driver after each operation and prevent retrograde movement.

Variations may be resorted to within the scope of the invention, and portions of the improvements may be used without others. 70

Having thus described my invention, I claim:

1. In a typewriting machine, the combination of type bars, devices selectively settable into positions to form actuating means 75 for their type bars, means to automatically lock said devices in such positions, and an intermittently operated pneumatic motor brought into operation by the setting of said devices to operate said devices and thereby 80 actuate the type bars, said devices being unlocked during the operation of the motor and thereby permitted to return to their initial positions.

2. In a typewriting machine, the combination of a key lever, a type bar, a lock for the 85 type bar, a device operated by the key lever to release the lock, and a pneumatic motor controlled by said device to actuate the type bar.

3. In a typewriting machine, the combination of a key lever, a type bar, an operating bar supported on the key lever and operable by the key lever in one direction, and pneumatic means controlled by such operation to 90 move said operating bar in a different direction and thereby operate the type bar.

4. In a typewriting machine, the combination of a rotary driver, a pneumatic motor, key levers, a valve operated by said levers to effect the operation of the motor, means operated by the motor to impart a step-by-step rotation to the driver in response to operation of the key levers, type bars, devices selectively operated by the key 100 levers into position to transmit motion from the driver to the type bars, and individual locks for the key levers set by the operation of the key levers and released by the selectively operated devices.

5. In a typewriting machine, the combination of a rotary driver, a bellows, operating means between the bellows and driver, type bars, manually controlled selective means to transmit motion from the driver 105 to the type bars, and locks to hold said selective means stationary in operative position.

6. In a typewriting machine, the combination of a plurality of type bars, actuating 110 devices therefor, a rotary driver, means to selectively operate and lock said devices in an operative position with respect to the type bars, a pneumatic motor, mechanism operated by the motor to rotate the driver, 115 and a valve controlling the operation of the motor, said valve being operable by each of the said type bar actuating devices.

7. In a typewriting machine, the combination of key levers, type bars, a wind motor, a rotary driver rotated by the motor to actuate the type bars, and to reset the motor for a subsequent operation, and locking latches for the key levers set by the operation of the key levers and released by the operation of said driver.
8. In a typewriting machine, the combination of a rotary driver, type bars, devices selectively operable to position for transmitting motion from the driver to the type bars, pawl and ratchet mechanism to intermittently operate the driver, a bellows, and an operating connection between the bellows and said mechanism.
9. In a typewriting machine, the combination of a bellows, a lever, a link between the bellows and lever, a pawl carried by the lever, a ratchet-wheel engaged by the pawl, a rotary driver having an axle to which said ratchet-wheel is secured, said driver comprising parallel spaced bars, type bars, selective devices movable into position to transmit motion from the driver to the type bars, and means to operate said selective devices.
10. In a typewriting machine, the combination of a bellows, a valve controlling the operation of the bellows, a key lever, a type bar, a rotary driver to actuate the type bar, pawl and ratchet mechanism for transmitting motion from the bellows to the said driver for actuating the latter, and mechanism operated by the key lever for opening said valve and thereby effecting the operation of the bellows.
11. In a typewriting machine, the combination of a bellows, a valve controlling its operation, a key lever, an operating bar set thereby, a mechanical connection from the operating bar to said valve for operating the latter, a type bar, a rotary driver for transmitting motion through said operating bar to the type bar, and mechanism operated by the bellows to impart a step-by-step rotation to said driver.
12. In a typewriting machine, the combination of type bars, key levers, operating bars supported on said key levers, a pneumatic motor, a valve controlling the motor, a universal bar adapted to be operated by each of the said operating bars, means operated by said universal bar for operating the valve and thereby effecting the operation of the motor, and means to selectively transmit motion from the motor through said operating bars to the type bars.
13. In a typewriting machine, the combination of type bars, selective devices to operate the type bars, a rotary driver to actuate said selective devices, a pneumatic motor controlled by said selective devices and operative to impart a step-by-step rotation to the driver, manual means for setting said selective devices, and means to individually lock said selective devices in set position.
14. In a typewriting machine, the combination of type bars, a rotary actuating device, a windomotor, keys, devices selectively set by said keys into position to transmit motion from said rotary device to the type bars independently of said keys, operating connections between said motor and rotary device, a valve operated by said keys to control the operation of the motor, and means to lock each key in operated position, said locking means released by the operation of said rotary device.
15. In a typewriting machine, the combination of a rotary driver, selectively operable devices settable into position to be operated by the said driver, keys to set said devices, pneumatic mechanism to operate the driver, type bars, intermediate operating mechanism between said devices and said type bars, and locks for the keys released by said operation of said selective devices.
16. In a typewriting machine, the combination of type bars, a rotary driver, pneumatic means to operate the driver, mechanism to transmit motion from the driver to the type bars, keys controlling said mechanism, and means to lock the keys in operated position, said locking means released by said transmitting mechanism.
17. In a typewriting machine, the combination of key levers, type bars, a rotary driver, a pneumatic motor, connections between the motor and driver, a valve operated by the key levers to effect the operation of said motor, selective mechanism set by the keys and actuated by the driver to transmit power to the type bars independently of the key levers and thereby operate the type bars corresponding to the operated key levers, and means to lock said selective mechanism in set position until actuated by the driver.
18. In a typewriting machine, the combination of a rotary driver, a pneumatic motor, operating means between the motor and driver, a set of type bars, keys, operating bars selectively settable by the keys to transmit motion from the driver to the type bars, and means to prevent the restoration of the operating bars to initial position before the corresponding type bars have been operated.
19. In a typewriting machine, the combination of types, operating bars, a rotary driver, means to selectively set the operating bars in the path of said driver, pneumatic mechanism to impart a step-by-step rotation to the driver to drive the set bars and thereby operate the corresponding types, and latches to prevent the return of the set bars, said latches released by the bars when the latter are operated by the driver.
20. In a typewriting machine, the combination of type bars, selective devices, means

to set said devices, means to lock said devices in set position, intermittently operated power mechanism brought into activity by the operation of said setting means to operate said devices and thereby operate the type bars, and means to release said devices.

21. In a typewriting machine, the combination of type bars, selective devices, means to set said selective devices, an intermittently operated driver controlled by said setting means to actuate said devices, and thereby operate the type bars, and locking means for said devices released by the actuation of said devices to operate the type bars.

22. In a typewriting machine, the combination of type bars, finger-keys, devices selectively operable by the keys into positions to form a power transmitting medium, means to lock said devices in said positions, and power mechanism brought into activity by the operation of said keys to actuate said devices when thus locked and thereby operate the type bars, said devices being automatically released when thus actuated and permitted to return to their initial positions.

23. In a typewriting machine, the combination of type bars, key levers, devices selectively movable by the key levers into position to form operators for the type bars, power mechanism for driving said operators, and means to lock each key lever in operated position, the key levers being released by said operators when the latter are driven by the power mechanism.

24. In a typewriting machine, the combination of a key lever, means to lock said lever when operated, an operating device set by the operation of the key lever, power mechanism to drive said device, and a type bar operated by said device, the key lever being automatically released by the said device when the latter is driven by the power mechanism.

25. In a typewriting machine, the combination of a key lever, an operating bar set thereby, means to lock said lever and bar in set position, a type bar, and power mechanism operable through said operating bar to actuate the type bar and simultaneously release the key lever.

26. In a typewriting machine, the combination of a type bar, an arm connected thereto, a key lever, an operating bar in position to be lifted by said lever, a locking latch to hold the lever and said operating bar after the latter is lifted, and power mechanism to drive said operating bar in a transverse direction and thereby operate said arm and type bar, said locking latch being in position to be released by said transverse movement of the operating bar.

27. In a typewriting machine, the combination of a horizontally disposed key

lever pivoted at an intermediate point, an operating bar supported on said lever and adapted to be lifted thereby, a latch to hold said lever in operated position, a type bar, power mechanism for driving the operating bar in a transverse direction, and means to transmit the transverse movement of the operating bar to the type bar and thereby actuate the type bar to printing position, said latch being positioned to be released by the operating bar during said transverse movement.

28. In a typewriting machine, the combination of type bars, a rotary driver, type bar actuating devices movable into position to be operated by the driver, means to intermittently operate the driver, and individual locks for said actuating devices operable automatically to prevent the return of the said actuating devices to initial position until said devices have been operated by the driver.

29. In a typewriting machine, the combination of type bars, locking means therefor, type bar actuating devices operable to release said locking means, key levers to set said actuating devices, means to lock the key levers in operated position, a rotary driver in position to operate said actuating devices, and thereby operate the type bars, and means to operate the driver.

30. In a typewriting machine, the combination of type bars, a rotary driver, type bar operating devices, means to move said devices into position to be operated by the driver, mechanism to intermittently rotate the driver, a motor to operate the said mechanism, and a locking latch for each of said devices automatically set when the device is moved to operative position and automatically released when the said device is operated by the driver.

31. In a typewriting machine, the combination of type bars, a motor, a rotary driver mechanically operated by said motor for actuating the type bars, devices controlling the operation of the motor, keys to set said devices, and means to lock said devices in set position, said locking means released by the operation of the rotary driver.

32. In a typewriting machine, the combination of an intermittently operated driver, a motor to operate the driver, type bars, mechanism to operate said bars operated by the driver, keys to set said mechanism, and means to lock said mechanism in set position until operated by the driver.

33. In a typewriting machine, the combination with type bars and key levers, of individual locking latches for said key levers to hold them in operated position, and means controlled by the operation of the key levers to actuate the type bars.

34. In a typewriting machine, the com-

6
bination with key levers, of spring-actuated latches to automatically engage said levers and hold them in operated position, type bars, and power mechanism controlled by 5 the key levers for actuating the type bars, said latches being automatically released by the power mechanism when the type bars are actuated.

35. In a typewriting machine, the combination with key levers pivoted intermediate 10 their ends, of spring latches to hold the individual levers in operated position, type bars, operating bars supported on the key

levers and lifted thereby to operative position, a motor to drive said operating bars, 15 and operating mechanism between said operating bars and the type bars, said latches being in the path of the said operating bars and actuated thereby to release the key levers when the operating bars are driven by the motor.
